UNITED STATES PATENT OFFICE.

RICHARD PAZOS-MARTINEZ, OF LOS ANGELES, CALIFORNIA.

AIRPLANE.

Application filed October 18, 1921. Serial No. 508,451.

To all whom it may concern:

Be it known that I, RICHARD PAZOS-MARTINEZ, a citizen of the United States, residing at Los Angeles, in the county of Los Angeles and State of California, have invented new and useful Improvements in Airplanes, of which the following is a specification.

This invention relates to an airplane and provides a new type of sustaining and propulsion means for machines of this general character.

The sustaining and propulsion means provided by this invention comprises a plurality of planes mounted on a carrier which may, as I hereinafter point out specifically, be in the form of an endless chain carried on spaced wheels so that it has a part moving rearwardly relatively to the machine and a part moving forwardly relative to the machine. The planes are mounted on the carrier so that they are movable to various positions relative thereto and means is provided for selectively holding the planes in various positions relative to the carrier at various parts of the carrier travel, for causing them to take positions at certain parts of the carrier travel so that they form a sustaining means and also a propulsion means for the machine. The means for selectively holding the planes in various positions relative to the carrier at various parts of the carrier travel permits of the planes being held to form a sustaining plane for the machine when or while they are at the forwardly moving portion of the carrier and in position to form propulsion means when they are at the rearwardly moving portion of the carrier, or permits of the planes being held relative to the carrier to form propulsion means for the machine at the forwardly moving portion of the carrier and be held relative to the carrier to form a sustaining plane while they are at the rearwardly moving portion of the carrier. When held in the first mentioned manner the machine is sustained and is propelled forwardly, and when the planes are held in the second mentioned manner the machine is sustained and the propulsion means tends to drive the machine rearwardly. In accordance with the invention the above mentioned mechanism is under full control of the operator so that he can cause the mechanism to operate in either of the manners just specified, at will. For instance, in practical operation, if the

mechanism is operating in the first mentioned manner and the machine is being propelled in a forward direction and it is desired to make a landing in a very limited space the operator can at the proper time cause the mechanism to operate in the second mentioned manner and thereby cause the machine to stop very quickly.

The generalities of the present invention as well as the details thereof will be best and more fully understood from the following detailed description of a typical form and embodiment of the invention throughout which reference is had to the accompanying drawings, in which:

Fig. 1 is a more or less diagrammatic side elevation of the machine provided by the invention and is a view showing the propulsion and sustaining means in position to drive the machine forwardly; Fig. 2 is a more or less diagrammatic plan view of the machine shown in Fig. 1; Fig. 3 is a diagrammatic view of the propulsion and sustaining means provided by the present invention showing it in position to operate in a manner to tend to or drive the machine rearwardly, being a view showing the propulsion and sustaining means in the position which is the reverse of that shown in Fig. 1. Fig. 4 is an enlarged vertical detail sectional view of the mechanism showing it in the position indicated in Fig. 1 and being a view taken as indicated by lines 4-4 on Fig. 2; Fig. 5 is a vertical transverse sectional view of the machine taken as indicated by line 5-5 on Fig. 4; Fig. 6 is an enlarged vertical detail sectional view of the parts shown at A in Figs. 1 and 4; Fig. 7 is a plan section taken as indicated by line 7-7 on Fig. 6; Fig. 8 is a detail sectional view taken as indicated by line 8-8 on Fig. 6; and Fig. 9 is a vertical detail sectional view taken as indicated by line 9-9 on Fig. 6.

Throughout the drawings numeral 10 designates the body of the machine and numerals 11 designate the propulsion and sustaining unit or means provided by the present invention and arranged in connection with or mounted on the body 10. In the particular machine which I herein set forth for the purpose of illustrating my invention there are two propulsion and sustaining means, one at each side of the body, and these means or units are arranged at the upper part of the body so that the sustaining plane is above the center of gravity of the

machine. The propulsion and sustaining means being at opposite sides of the longitudinal center line of the machine tend to hold it in lateral equilibrium. It will be obvious that the particular arrangement and number of propulsion and sustaining means may be varied and that the particular number and arrangement of propulsion and sustaining means set forth in this disclosure 10 of the invention is only typical and for purposes of illustration.

The body 10 which I have shown in the drawings is of more or less conventional design and construction. An operator's seat 15 12 is provided in the forward portion of the body and suitable elevating planes 13 and a rudder 14 are provided at the rear end of the body. Power means 15, preferably an internal combustion engine such as 20 is commonly used in machines of this character, is carried in the body 10 for the purpose of operating the propulsion and sustaining means 11 provided by the invention.

In accordance with the present invention 25 each propulsion and sustaining means 11 comprises, generally, a plurality of planes 16, a flexible carrier 20 for the planes, preferably in the form of an endless chain, spaced wheels 21 for carrying the carrier so 30 that it has, when in operation, a course moving substantially rearwardly and a course moving substantially forwardly. When the carrier 20 is in the form of an endless chain the wheels 21 may be sprocket wheels and 35 the carrier may be operated by rotating one of such sprocket wheels. In the machine illustrated in the drawings the forward sprocket wheels 21 of each of the propulsion and sustaining means 11 are mounted on a 40 single shaft 22 supported transversely of the body 10 in a bearing member 23 mounted on the top of the body 10. The rear sprocket wheels 21 of the two propulsion and sustaining means 11 are mounted on a single 45 shaft 24 carried transversely of the body 10 at an elevation somewhat below (for a reason hereinafter explained) that of the shaft 22 by a bearing member 25, mounted on the body 10. The driving connection between 50 the power means 15 and the propulsion and sustaining means 11 comprises a counter-shaft 26, a bevel gear drive 27 between the shaft 28 of the countershaft, and a chain drive connection 29 between the counter-shaft 26 and the shaft 24 on which is 55 mounted the rear sprocket wheels 21 of the propulsion and sustaining means. The invention of course is not limited to this particular driving connection between the power 60 means and the propulsion and sustaining means and it will be obvious that various arrangements and constructions other than the one just mentioned might be advantageously employed.

65 I will now proceed to describe in detail

the construction and operation of one of the propulsion and sustaining means 11 it being understood of course that such description applies also to the other propulsion and sustaining means. The carrier 20 or chain 20 70 as I will hereinafter refer to it, comprises a plurality of links 30 which carry shafts 31 on which are carried planes 32; and links 33 which connect the links 30. Shafts 31 are rotatable in their bearings 38; and the 75 planes are arranged on the shafts so as to have a longer surface on one side of the shaft than on the other, so that wind pressure will cause certain movements of the planes as hereinafter described. Sprocket 80 wheels 21 have teeth 34 which co-operate with and carry the links 30 and 32, and have openings or recesses 35 between certain of the teeth 34 for the reception of certain mechanism which is carried by the links 30 85 and which will be hereinafter described in detail. The construction and operation of the chain 20 and sprockets 21 is very similar to that of an ordinary chain and sprocket construction and will be readily understood 90 from inspection of the drawings. The links are made relatively long so as to give to the chain a good stability in supporting the planes in their selected positions against wind pressure. Each link 30 is formed with 95 a bearing 38 which rotatably carries the shaft 31 transversely of the chain. The shaft 31 extends on either side of the chain 20 and has fixed on it at each side of the chain a plane 16. The planes 16 on each 100 shaft at the two sides of the chain form pairs, and are preferably of the same size and weight so that they balance each other and are fixed on the shaft 31 so that their surfaces are coplanar. The shaft 31 being 105 rotatably carried in the bearing 38 of the links, the planes 16 can be swung or rotated to various positions to lie in various planes.

In operation when the links 30 are at the rearwardly moving course of the chain and the planes 16 are positioned so that they lie in a substantially vertical plane they will 110 obviously act upon the air in a manner which will cause the machine to be propelled forwardly; and when the links are at the forwardly moving course of the chain and the planes are turned or disposed so that they are substantially horizontal or lie substantially parallel to the course, then they form a supporting or sustaining plane. In the 115 particular machine illustrated in the drawings the rear sprockets 21 being somewhat below the forward sprocket wheels, the several planes 16 at the rearward moving portion of the chain when in a vertical position 120 will act continuously on new air and will not follow directly in each other's paths in a manner to merely churn the air, and the planes at the forwardly moving course of the chain, when disposed so that they lie in 125

the plane of such course, cooperate to form Fig. 3) to a horizontal position and as they a more or less continuous sustaining plane. This sustaining plane will have an angle of incidence dependent upon the relative vertical locations of the forward and rear sprockets; and further, this plane, due to the flexibility of the chain, will take, under the air pressure, a curved shape (see Figs. 1 and 3) that will give best reactance on the air. When the planes 16 carried by the several shafts 31 are held in the manner or positions just described, the machine will be propelled forwardly and the direction of travel of the air relative to the machine will be that indicated by the arrow E in Figs. 1 and 3. Assuming for example that the chain is operating so that its uppermost course travels rearwardly the planes 16 upon being released when they reach the rear sprocket wheel 21 and decrease their relative rearward movement by virtue of moving around the sprocket, will be carried by the movement of the air relative to the machine in the direction indicated by the arrow at that point in Fig. 1 and will, if not restricted in any way, assume and keep a substantially horizontal position. They will thus reach the position relative to the chain in which they are held while they are at the forwardly moving course of the chain. The change of position of the planes from normal to parallel to the chain will commence at the time the planes reach the rear sprocket 21 and will be completed at about the time they leave the rearmost sprocket wheel 21 where the chain is also substantially horizontal. The planes upon reaching the forward sprocket after being at the forwardly moving course of the chain will if released remain in a substantially horizontal position as they pass around the sprocket, being held in that position by the air movement relative to the carrier. While remaining in a horizontal position as they pass around the forward sprocket wheel 21 the planes will reach a position transverse of the chain which position is the position in which they are held while they are at the rearwardly moving course of the chain.

If the planes 16 are held in a vertical position while they are at the forwardly moving course of the chain they will act upon the air to tend to propel the machine rearwardly, or if the machine is moving forward they would tend to stop it, and if they are held in a substantially horizontal position while at the rearwardly moving course of the plane they will cooperate to form a more or less continuous supporting or sustaining plane. If upon reaching the forward sprocket from the forwardly moving course of the chain and in a vertical position the planes 16 are released, the movement of air will cause them first to swing in the direction indicated by the arrow B (see

5 10 15 20 25 30 35 40 45 50 55 60 65 70 75 80 85 90 95 100 105 110 115 120 125 130

The present invention provides means for holding the planes relative to the chain in the several manners above described and provides control means for said holding means whereby the planes can be selectively held in the manners above described to cause the mechanism to operate in either of the manners above described. To cause the machine to operate as illustrated in Fig. 1 the planes 16 must be released at the forward sprocket at about the point marked release in that figure, must be caught at the forward sprocket at about the point marked catch, must be released at the rear sprocket at about the point marked release, and must be caught at the rear sprocket at about the point marked catch. To cause the machine to operate in the manner illustrated in Fig. 3 the planes must be released at the forward sprocket at the point marked release, in that figure, must be caught at the forward sprocket at the point marked catch, must be released at the rear sprocket at the point marked release, and must be caught at the rear sprocket at the point marked catch. To hold the planes 16 in the various positions relative to the chain 20 I show a notched disk 45 fixed concentrically on each shaft 31 at the outer side of the chain, and I provide a catch or pawl 46 in connection with each link 30 to cooperate with the notched disk 45. In the construction shown in the drawings the notched disk 45 is not secured directly to the shaft 31 but is secured to the outer plane 16 so that it over-

hangs the bearing 38 which projects from the side of the link. The disk 45 has several suitably arranged and spaced notches or recesses. In the present case the disk has three notches 47, 48, and 49 spaced substantially 90° apart around its periphery. The pawl 46 is slidably carried in a carrier 50 so that it is movable in a direction normal to the shaft 31 and radially relative to the sprocket wheels when at the sprocket wheels. The pawl is adapted to cooperate with or extend into the notches 47, 48 and 49. A spring 51 is arranged in connection with the pawl 46 to normally hold it out or in a position to cooperate with a notch. When the pawl 46 is in one of the notches in the disk 45 it will positively hold the shaft 31 and planes 16 against movement relative to the link 30. The notches 47, 48 and 49 being at various positions around the disk 45 the pawl when in different notches will hold the planes in different positions relative to the chain. To carry out the operation above described it is only necessary to hold the planes in three different positions relative to the chain, which positions are 90° apart, thus making it necessary to provide only three notches in the disk 45. It will be obvious that the planes could be held in any position relative to the chain and in numerous different positions relative to the chain by simply providing notches in the proper number and relation in the disk 45. In the present case when the pawl 46 is in the notch 47 the planes 16 are at substantially right angles to the chain with their large ends extending outwardly from the chain, as is desired at the forwardly moving course of the chain when it is desired to tend to propel the machine rearwardly. When the pawl 46 is in the notch 48 the planes are substantially parallel to the chain with their large ends extending in the direction opposite to that in which the chain is moving as is desired at the rearwardly moving course of the chain when the planes are vertical at the forwardly moving course of the chain and as is desired at the forwardly moving course of the chain when the planes are vertical at the rearwardly moving course of the chain. When the pawl 46 is in the notch 47 the planes are at substantially right angles to the chain with their large ends extending inwardly, as is desired at the rearwardly moving course of the chain when it is desired to propel the machine forwardly. From the foregoing description of the manner in which the planes will move relative to the chain, when released at certain parts of the sprocket, it will be understood how releasement of the pawls from the notches at the proper times and for the proper period of time will allow the planes to change position relative to the chain in the desired manner and will

also allow the pawls to transfer from one notch to another.

In order that the pawls 46 may be released at the desired points and for the desired periods, or, in other words, to provide a control for the holding means, a roller 60 is connected with each pawl 46 and suitable cams and tracks are provided for cooperating with the rollers to move and hold them at the desired times and for the desired periods and thereby cause the desired movements of the pawls 46 at the desired times and for the desired periods. The rollers 60 are carried on extensions 61 of the pawls so that they are at the inside of the chain. The carriers 50 for the pawls and their extensions 61 extend into the recesses 35 in the sprockets when the links 30 are at the sprocket. In the particular machine set forth in the drawings there is a fixed cam strap 62 at the inner side of the forward sprocket wheel 21, shaped and positioned to engage the rollers 60 upon the links 30 reaching the forward sprocket to the rollers inwardly so that the pawls are retracted from the notches. The cam strap 62 is of such extent as to hold the pawl retracted through approximately 90° movement. The cam strap 62 may be carried by arms 63 extending from the bearing member which carries the shaft 20. A track member 64 is slidably carried on the outside of the cam strap 62 so that it can be moved to a position where it forms a continuation of the cam strap and thereby causes the rollers to be held retracted through substantially 180° movement. The track 64 may be carried by arms 65 extending from a sleeve 66 which is rotatably carried on the outer portion of the bearing member 23. In practice the cam strap 62 may be made to retract the pawls enough in excess of that actually required to retract them from the notches so that they will not extend into the notches when held by the track 64 which does not hold them retracted quite as much as the cam strap does. At the rear sprocket 21 there is a cam strap 70, similar in construction, mounting, and operation to the cam strap 62 at the forward sprocket, and there is a track 71 similar in construction and operation to the track 64 at the forward sprocket 21. The cam strap 70 is carried by arms 72 extending from the bearing member which carries the shaft 24 and the track 71 is carried on the bearing member which carries the shaft 24. Without further explanation it will be understood how the pawls will be operated to release and hold the planes so that they are in the various positions indicated in Fig. 1 when the track 64 is positioned as shown in Fig. 4 and the track 71 is extended as shown in Fig. 4. It will also be obvious that the planes will be released and held so that they are in the various positions indicated in Fig. 3 when the track 74 is extended relative to

- the cam strap 62 and the track 71 is not extended. For the purpose of controlling or operating the tracks 64 and 71 together I provide the rotatable sleeves 66 and 76, 5 which carry the tracks 64 and 71, respectively, with arms 80 and 81, respectively. A connecting rod 82 extends between the arms 80 and 81 connecting them so that movement of one will cause movement of the other. 10 With the tracks 64 and 71 connected in the relative positions shown in Fig. 4 it is possible, by simply moving the connecting rod 82, to simultaneously operate both of the tracks and it is impossible for the tracks to 15 get out of position relative to each other. In the particular machine illustrated in the drawings the rod 82 of the two propulsion and sustaining means 11 pass the operator's seat 12 so that they can be conveniently 20 reached and operated by the operator. Although means might readily be provided for interconnecting the two propulsion and sustaining means 11 so that they can be simultaneously controlled or operated from a 25 single member it is preferred that they be left so that they can be independently controlled or operated as the machine might be directed by adjusting the two means 11 to operate differently. 30 Having described only a preferred embodiment of my invention I do not want to limit myself to the specific details herein set forth but wish to reserve to myself various changes and modifications which may appear to those skilled in the art and which may fall within the scope of the following claims. 35 Having described a preferred form of my invention, I claim:
1. Airplane propulsion mechanism, embodying an endless carrier and spaced driving wheels therefor to drive the carrier in two opposite courses, planes movably mounted on the carrier, and means mounted on the carrier to hold the plane either substantially parallel or normal to its movement, and stationary manually controllable means to control the plane holding means. 40
2. Airplane propulsion mechanism, embodying an endless carrier and spaced driving wheels therefor to drive the carrier in two opposite courses, a plurality of planes spaced along the carrier and pivotally mounted thereon, a releasable holding device mounted on the carrier near each plane and adapted to hold the plane in a position substantially parallel to the carrier or substantially normal to it, and stationary cam mechanism to actuate the holding means. 50
3. Airplane propulsion mechanism, embodying an endless carrier and means to move it longitudinally, planes pivotally mounted on the carrier, each plane comprising two 55 parts, lying on opposite sides of the carrier and a common shaft on which both parts are mounted; and means to hold the planes in fixed definite relation to the carrier. 60
4. A flying machine of the class described having a body, an endless driving means 70 connected to each side of the body, a pair of plane members pivoted to said driving means, means for moving said plane members in one direction substantially in a horizontal position, means for moving said plane members in the opposite direction in substantially a vertical position, means for holding the plane members in their said positions and manually operated controlling means for actuating said plane holding means. 75
5. A flying machine having a body, propulsion means mounted on opposite sides of the body, each of said propulsion means comprising a pair of laterally spaced planes, 80 means for alternately moving said planes in opposite directions, means for holding the planes in a horizontal position when they are moved in one direction, means for holding the plane in a vertical position 85 when moved in the opposite direction, and manually operated controlling means for actuating the plane holding means to control the position of the plane relative to the body. 90
6. A propulsion mechanism for flying machines comprising an endless carrier, a pair of laterally spaced plane members journaled to said carrier, means mounted on said carrier for holding the planes substantially parallel to their movement in one direction, and perpendicular to their movement in the opposite direction. 95
7. A propulsion mechanism for flying machines comprising an endless carrier, a 100 pair of laterally spaced plane members journaled to said carrier, means mounted on said carrier for holding the planes substantially parallel to their movement in one direction, and perpendicular to their movement in the opposite direction, and means for automatically releasing said holding means at predetermined points in the path of movement of the carrier. 105
8. A propulsion mechanism for flying 110 machines comprising an endless carrier, a pair of laterally spaced plane members journaled to said carrier having longer surfaces on one side of the carrier than the other, means mounted on said carrier for holding the planes substantially parallel to their movement in one direction and perpendicular to their movement in the opposite direction. 120
- In witness that I claim the foregoing I have hereunto subscribed my name this 23d day of September 1921. 125
- RICHARD PAZOS-MARTINEZ.
